UNITED STATES PATENT OFFICE.

PETER A. LALLE AND CLAUDE F. FOWLER, OF BUFFALO, NEW YORK, ASSIGNEES OF
ONE-THIRD TO SEBASTIAN L. PETRINO, OF BUFFALO, NEW YORK.

AMUSEMENT APPARATUS.

Application filed July 7, 1921. Serial No. 483,028.

To all whom it may concern:

Be it known that we, PETER A. LALLE and CLAUDE F. FOWLER, citizens of the United States, residing at Buffalo, in the county of Erie and State of New York, have invented certain new and useful Improvements in Amusement Apparatus, of which the following is a specification.

Our invention relates to an amusement apparatus and has particular reference to an apparatus embodying a track-guided truck carrying a passenger mount.

One of the objects of our invention is to provide an amusement apparatus in which a number of traveling units are arranged in racing formation and adapted to be propelled along correspondingly trending tracks.

Another object of our invention is to embody in the apparatus, a truck, an electric motor carried thereby, a track associated with a third or contact and means to automatically stop the truck when coming in contact with a truck ahead.

Another object of our invention is the provision of an amusement apparatus in which two or more traveling units may travel on each track and which is equipped with means to automatically shut off the power for driving each traveling unit when it comes in contact with one preceding it.

A further object is to provide means for simultaneously shutting off the power and applying brake mechanism to each unit when the front end thereof comes in contact with the traveling unit ahead on the same track.

A still further object is to provide novel means for setting the passenger mount in motion when the traveling unit is moved along the track.

A still further object is to so construct the passenger mount that the weight carried thereby is diverted from the mechanism which places the mount in motion.

A still further object is to provide means controlled by an attendant to stop each unit and simultaneously shut off the power therefrom when there appears to be a probability of a rear end collision of traveling units on the same track.

A still further object is to provide a device of this kind having a plurality of parallel tracks, a platform covering said tracks,

and traveling units movable along said tracks and controlled from a fixed station having means for cutting out any one of said units.

With the above and other objects in view to appear hereinafter, the invention consists in an amusement device having parallel tracks, and traveling units arranged in racing formation, including passenger mounts, preferably in the form of horses.

It further consists in means for automatically braking each traveling unit when it comes in contact with the rear end of a unit ahead on the same track; also in means for cutting off the power at such times.

It further consists in means for stopping each traveling unit and simultaneously shutting off the power therefrom to prevent rear end collisions of traveling units on the same track.

It further consists in so supporting the passenger mount that the weight thereof and of the passenger mounted thereon is not imparted to the mechanism, and in giving each mount individual movement; and it still further consists in the novel features of construction and in the arrangement and combination of parts to be hereinafter described and more particularly pointed out in the subjoined claims.

In the drawings:

Fig. 1 is a sectional elevation through a portion of the apparatus.

Fig. 2 is an enlarged transverse section taken on line 2-2, Fig. 1.

Fig. 3 is a sectional plan view of one of the trucks of the apparatus and the track and third rail associated therewith.

Fig. 4 is a detached perspective view of a portion of the automatic brake and cut-out mechanism.

Fig. 5 is a perspective view of a portion of the cut-out mechanism.

Fig. 6 is a transverse section through the roller contact forming part of the automatic cut-out mechanism.

Fig. 7 is an enlarged section taken on line 7-7, Fig. 6.

Fig. 8 is a longitudinal section taken on line 8-8, Fig. 3.

Fig. 9 is an enlarged transverse section taken on line 9-9, Fig. 1.

Fig. 10 is a diagrammatic view illustrating one of the circuits of the apparatus,

which includes the motor of a truck, the third or contact rail associated with one of the tracks, and a portion of said track.

Fig. 11 is a detail view showing one means 5 for electrically operating the brake rails arranged at intervals along the tracks.

Fig. 12 is a diagrammatic view of the tracks and the electric circuits controlled by an attendant arranged at a fixed point and 10 having full view of the tracks at all points thereof.

In the drawings the tracks are designated by the numerals 12, 13, 14, 15, and 16, each 15 track comprising two rails. We have shown five tracks, although any other number may be used. These tracks are shown in Fig. 12 as being parallel, and while they may be used, we preferably employ endless tracks, either circular, oval, or of other endless formation. 20

Associated with the tracks are third or contact rails 17, 18, 19, 20, and 21, one third or contact rail extending along each track; as clearly shown in Fig. 12. 25

Arranged above the track is a suitable platform 22 supported in any practicable manner from the ground and covering all tracks. The platform has a slot or opening 23 arranged in a plane centrally between the rails of each track, for a purpose to appear hereinafter. The platform also has cross beams 24, longitudinal beams or joists 25 spaced apart and supported by said cross beams, and flooring or other suitable material 26 fastened to said longitudinal beams or joists, the slots or openings 23 in the platform being formed in the flooring or covering material, as it may be termed. 30

One or more traveling units 27 are adapted 40 to travel along each track. When more than one is used on a track, they travel at intervals, one in rear of the other, it being understood that the track, when made endless, may have a lineal measurement of several hundred feet so that several traveling units may be placed in operation at the same time. Each traveling unit comprises a truck 28 and a passenger mount 29 supported by the truck. 50

Each truck 28 comprises a frame having side members 30, end members 31, and transverse connector or cross members 32 spaced apart in convenient manner to rigidly connect the side members 30 and also to serve as convenient supports for the various mechanisms carried or supported by the truck. At the front end of the truck, traction wheels 33 are provided which travel along the track, these wheels being mounted on suitably journaled axles 34. 55

At the rear of the truck, driving wheels 35 are provided which travel on the track and are secured to an axle 36. 60

Connecting the rear end member 31 with

the rearmost transverse connector or cross member 32, are supporting members 37 on which is mounted an electric motor 38, which is preferably a variable-speed motor, and to the shaft thereof a pinion 39 is secured which meshes with a gear wheel 40 secured to the rear axle 36. Said axle also has a gear wheel 41 secured thereto, which is in mesh with a gear wheel 42 fastened to a transverse shaft 43 journaled in suitable bearings 44 fastened to the side members 30 of the truck. The shaft 43 has a bevel gear-wheel 45 secured thereto, which is in mesh with a bevel gear-wheel 46 fastened to the rear end of a longitudinally-disposed shaft 47 journaled in suitable bearings 48 fastened to two of the transverse connecting members 32 of the truck. 70 75 80

At the front end of the longitudinally-disposed shaft 47, a bevel gear-wheel 49 is secured, which is in mesh with a bevel gear-wheel 50 fastened to a transverse shaft 51 journaled in the lower ends of spaced standards 52 rising from and being fastened to two of the transverse connecting members 90 95 99 of the truck, said standards having depending portions 53 in which the shaft 51 is journaled.

When the motor 38 is rotated, the rear or driving wheels 35 are rotated through the medium of the pinion 39 and gear-wheel 40. At the same time, motion is transmitted from the gear-wheel 41 to the transverse shaft 51 through the medium of the gear-wheel 42, transverse shaft 43, bevel gear-wheels 45 and 46, shaft 47, and bevel gear-wheels 49 and 50. 100

Each of the passenger mounts, which may be of any shape and adapted to carry one or more passengers, is preferably in the form of a horse, suitably fashioned out of wood or other material, and it is secured to a rod 54 passing downwardly through a rocking guide-member 55. Said guide-member has a narrow portion 56 extending through the co-operating slot or opening 23 in the platform 22. The guide-member has laterally-disposed trunnions 57 journaled for rocking movement in the upper ends of the standards 52, and at its lower end it also has laterally-extending trunnions 58 on which rollers 59 are rotatably mounted, which ride in segmental guide-slots 60 arranged in the standards 52. By pivotally mounting the rocking guide-member in the upper ends of the standards and having a portion thereof extending upwardly through the slot or opening 23 in the platform and a portion extending downwardly a distance between the two standards 52, it may oscillate so that its lower portion swings rearwardly while its upper portion swings forwardly, and reversely. 110 115 120 125

Secured to the upper end of each rocking guide-member 55 are foot rests 61 on which 130

a person seated on the passenger mount or horse may conveniently rest his feet. Surrounding the rod 54, which may be termed a supporting rod, is a weight-carrying 5 spring 62 having the upper end thereof bearing against the passenger mount or horse and the lower end thereof against the upper end of the rocking guide-member 55. The lower end of said rod is secured to an 10 eccentric strap 63 which encircles an eccentric 64 fastened to the transverse shaft 51, which for convenience may be termed an eccentric shaft. The rotation of the eccentric shaft 51 will cause the eccentric 64 to impose 15 an oscillating movement to the lower end of the supporting rod 54, thus causing the upper end thereof to oscillate and have a component upward and downward movement, which will give the passenger mount or horse a motion simulating the action of a horse when trotting. As the weight-carrying 20 spring 62 is quite powerful, it serves to carry the weight of the mount and the passenger thereon, thus relieving the eccentric 25 64 of strain and allowing it free action without binding of the eccentric strap 63 thereon. Since the supporting rod 54 is guided in the rocking guide-member 55, said guide-member also rocks on the trunnions 30 or pivots 57 and, therefore, carries the feet of the passenger resting upon the foot rests 61 forwardly with the body when the passenger mount or horse rocks.

At opposite sides of each standard 52, 35 roller-supporting brackets 65 are suitably secured to the truck, each bracket having a roller 66 therein. Fastened to the under side of the cross beams 24, directly above the line of travel of said rollers, are flat tracks 40 67 in contact with which said rollers may travel. However, to eliminate unnecessary resistance to the travel of the passenger unit, said rollers are slightly spaced from the tracks 67 and serve merely to prevent lifting 45 of the truck from the track 12, thereby serving as a safety device, and as a guide to prevent the truck leaving the track 12.

Fastened to one of the transverse connector or cross members 32 of the truck at a point between the standards 52 and the rear-most transverse connector member is a vertically-disposed guide 68 in which is arranged for vertical movement a brake actuator member 69 pivotally connected at its 55 upper end, as at 70, to a transversely-disposed actuator lever 71, said actuator lever having a slot 72 therein through which the pivot 70 is passed. One end of said actuator lever is pivotally secured to one end of a horizontally-disposed brake lever 73 pivotally attached between its ends, as at 74, 60 within a standard 75 fastened to one of the transverse connector or cross members 32.

The horizontally-disposed brake lever 73 65 extends forwardly a considerable distance

from its pivot 74, and projects beyond the front end of the truck, as at 76, its front end being forked to receive a roller 77, which is rotatable therein. To retain the front end of said brake lever 73 in lowered position, 70 a retractile spring 78 is provided, one end thereof being fastened to said brake lever and the other end to the front end member 31 of the truck.

The transverse actuator lever 71 extends 75 downwardly from a point beyond its slot 72 and is pivotally secured, as at 79, to a bracket 80 fastened to the under side of the transverse connector or cross member 32 having the vertically-disposed guide 68 secured thereto, it being directed underneath one of the side members 30 of the frame and having an electric contact 81 fastened thereto and insulated therefrom, as at 82, and adapted for co-action with the third rail 85 17, 18, 19, 20 or 21, as the case may be. At the outer end of said actuator lever a U-shaped supporting member 83 is secured, said supporting member having a roller-receiving frame 84 pivotally secured therein, and a brake roller 85 mounted in said frame, the axis of said brake roller being at right angles to the pivots of said frame, as best shown in Fig. 5.

At regular intervals along each track, a 95 brake rail 86 is arranged, which is adapted to be engaged by the brake roller 85 when the latter is depressed. These brake rails are comparatively short and the ends thereof distant from the starting point of the traveling units are loose and capable of being forced upwardly. For this purpose an armature coil 102 may be positioned underneath the loose end of each brake rail and be provided with a core 103 adapted to move 100 upwardly and downwardly therein, said armature coil having current-conducting wires 104, 105 connected thereto which may be led to within convenient reach of the attendant controlling the current through the several 105 motors of the traveling units, or to another attendant. The upper end of the core 103 is adapted to bear against the under side of the loose end of the rail, and when the armature coil 102 is energized, the core will be moved upwardly and cause the loose end of the rail to rise. Each armature coil is individually controlled by an attendant who will be in a position to have a full and clear 110 view of all traveling units in motion, and when he discovers that one unit is too closely approaching another on the same track, will energize the armature coil of the 115 brake rail being approached by the traveling unit likely to cause a rear end collision and will therefore elevate the loose end of said rail, with the result that the brake roller 85 of the approaching traveling unit will be elevated, thus lifting the co-operating contact 81 from the third rail and cutting off 120 125 130

the power from the motor on said traveling unit, at the same time stopping said traveling unit by reason of the resistance offered by the elevated brake rail to the further traveling movement of the brake roller in contact therewith.

As we lay no claim to any particular device or mechanism for lifting the loose ends of the brake rails, we do not deem it necessary to illustrate any circuit in connection with the armature coil illustrated in Fig. 11, due to the fact that it is within the skill of any ordinary electrician to connect the armature coils with a source of electricity and include in the circuit, suitable switches or other make-and-break devices for selectively and individually energizing the coils.

Each truck has a yielding bumper 87 at its front end and a similar bumper 88 at its rear end alined therewith, and it also has an inclined member or skid 89 secured to the rear end member 31. Therefore, when one truck closely approaches a preceding truck on the same track, the roller 77 at the front end of the horizontally-disposed brake lever 78 will come in contact with the skid of the preceding truck and ride upwardly on the same, with the result that the front portion of the brake lever will be elevated, thereby causing the rear portion to descend. This causes that portion of the transverse actuator lever between its pivots and the brake lever to descend, while the portion extending outwardly from its pivot will rise, thereby elevating the contact 81 from the third rail 20, and breaking the circuit, which causes the truck to stop.

The actuator member 69 is provided with a pair of lugs 90, between which is pivotally connected one end of a link 91 having its other end secured to a transversely-disposed brake rod 92 whose ends are slidably arranged in guides 93 secured to opposite side frame members 30. Brake shoes 94 are provided, which are held in line with the rear or driving wheels 35 and which have arms 95 extending therefrom, said arms being secured to the brake rod 92. With the parts in normal position, the link 91 is directed upwardly and forwardly from the brake rod, and when said actuator member 69 is depressed, this link moves into or approaches a horizontal position, with the result that the brake rod 92 is moved rearwardly and forces the brake shoes 94 in contact with the rear or driving wheels 35.

The attendant controlling the current to the motors of the several trucks may shut off the current completely by means of a switch 96, to which the main or power feeding wires 97 are connected. The switch 96 is connected to a controller 98 by means of wires 99, 100, thus when the switch 96 is open, no current is passed to the controller, but when said switch is closed, current is de-

livered to the controller and shut off and regulated by a suitable handle 101, or otherwise.

As clearly shown in Fig. 12, the controller 98 has current-conducting wires 106, 107 connected thereto, which lead to double-pole switches 108, and each of said switches has connection by wires 109, 110 with one of the rails of a track and with the third rail co-operating therewith; thus, by closing the double-pole switches 108, current will be passed through the motors 38 of the traveling units on the tracks, and by opening any one or more of said switches, the corresponding motor will be cut out, thereby stopping the traveling unit or units on the track having the open switch 108 connected therewith.

In Fig. 12 the tracks are shown trending in corresponding directions and the traveling units on the tracks are adapted to be arranged in line transversely or, in what we term "racing formation." Therefore, with all the double-pole switches 108 closed and the switch 96 closed, current can be directed to the motors of the traveling units on the several tracks by manipulating the controller 98 or, if desired, one or more of the traveling units may be cut by opening the corresponding switch 108, thus making it unnecessary to cause any unit to travel along the track except when occupied by a passenger or passengers.

Having thus described our invention, what we claim is:—

1. In an amusement apparatus, a plurality of guided traveling units arranged in racing formation, and means for electrically controlling the movements of said traveling units from a common point and for selectively cutting out any of said units from said common point.

2. An amusement apparatus, comprising a plurality of correspondingly trending tracks, a plurality of traveling units on each of said tracks, means controlled from a distant point for causing movement of said traveling units along said tracks, and means to prevent the traveling units on each track from closely approaching each other.

3. An amusement apparatus, comprising a track, a plurality of traveling units on said track, a motor on each of said traveling units, a third or contact rail along said track serving as a means of conducting current to said trucks, a contact on each truck traveling in engagement with said third or contact rail and having electrical connection with said motor, and means to automatically disengage the contact of each truck from said third or contact rail when the truck closely approaches a truck in advance thereof.

4. An amusement apparatus, comprising a plurality of correspondingly trending tracks, a plurality of trucks adapted for traveling movement on each track and hav-

- ing driving wheels connected by an axle, a motor on each truck for operating the driving wheels thereof, an eccentric shaft, means for rotating said eccentric shaft from said 5 axle, an eccentric on said eccentric shaft, standards rising from said trucks, a guide element pivotally secured to said standards, a supporting rod guided for movement in said guide element and having an eccentric 10 strap surrounding said eccentric, and a passenger mount secured to the upper end of said supporting rod.
5. In an amusement apparatus, a truck having a shaft journaled thereon and means for rotating said shaft, an eccentric on said shaft, a vertically-disposed supporting rod guided for combined vertical and oscillating movement and having an eccentric strap surrounding said eccentric, and a passenger 15 mount secured to the upper end of said supporting rod.
6. In an amusement apparatus, the combination with a traveling truck, of a vertically-disposed supporting rod, a passenger mount secured to the upper end of said supporting rod, operating means at the lower 20 end of said supporting rod for causing said rod to reciprocate vertically and simultaneously oscillate, and means for relieving the operating means of the weight of said passenger mount and the passenger thereon.
7. In an amusement apparatus, the combination with a truck, of a vertically-disposed supporting rod, means at the lower 25 end of said rod for reciprocating the same, a passenger mount secured to the upper end of said supporting rod, and yielding means for supporting the major portion of the weight carried by said passenger mount.
- 30 8. An amusement apparatus, comprising a plurality of correspondingly trending tracks, a platform above and spaced from said tracks, said platform covering all of said tracks and having slots therein trending in the direction of said tracks, one slot being arranged centrally over each track, a truck arranged for traveling movement on each track, driving wheels on said truck connected by an axle, a motor geared to said 35 axle, passenger mounts above said platform, each mount having a supporting element extending downwardly through a slot of said platform and receiving support from the corresponding truck, and means driven from the driving axle of each truck for giving the supporting element of said truck an upward and downward movement and a component 40 forward and backward movement.
- 45 9. An amusement apparatus, comprising a truck having a driving axle at its rear end and driving wheels on said axle, a shaft parallel with said driving axle, a gear wheel on said axle, a counter shaft between said axle and said first-mentioned shaft, a gear 50 wheel on said counter shaft, a longitudi-
- nally-disposed shaft between said first-mentioned shaft and said counter shaft, a bevel gear-wheel on said counter shaft, a bevel gear-wheel at the rear end of said longitudinally-disposed shaft in mesh with the bevel 55 gear-wheel on said counter shaft, a bevel gear-wheel at the front end of said longitudinally-disposed shaft, a bevel gear on said first-mentioned shaft in mesh with the bevel gear of said longitudinally-disposed shaft, 60 an eccentric on said first-mentioned shaft, a supporting rod extending upwardly from said eccentric and having an eccentric strap at its lower end surrounding said eccentric, a guide element pivotally secured in a plane 65 above said first-mentioned shaft and having said supporting rod extending therethrough, and a passenger mount secured to the upper end of said supporting rod.
10. An amusement apparatus, comprising a truck, a pair of spaced standards rising from said truck, a guide element between said standards having laterally-disposed trunnions mounted for rocking movement in the upper ends of said standards, said guide 70 element having laterally-extending trunnions beneath said first-mentioned trunnions guided for movement in said standards, a supporting rod guided for movement in said guide element and having an eccentric strap 75 at its lower end, an eccentric within said strap, means for rotating said eccentric, and a passenger mount secured to the upper end of said supporting rod.
11. An amusement apparatus, comprising a platform having a slot arranged lengthwise therein, a truck beneath said platform having a pair of spaced standards rising therefrom, said standards being provided with segmental guide slots a distance from 80 their upper ends, a guide element arranged for oscillating movement and having laterally-disposed trunnions between its ends journaled in the upper ends of said standards, said guide element extending upwardly 85 through the slot of said platform and having laterally-disposed trunnions at its lower ends, rollers on said trunnions guided in the segmental slots of said standards, foot rests secured to the upper end of said guide element and extending upwardly and outwardly therefrom, a supporting rod guided for movement in said guide element and having an eccentric strap at its lower end, an eccentric within said eccentric strap, means 90 for rotating said eccentric, and a passenger mount secured to the upper end of said supporting rod.
12. An amusement apparatus, comprising a platform having a slot arranged lengthwise therein, a truck guided for traveling movement beneath said platform and having a guide element pivotally secured between its ends and extending upwardly 95 through said slot, a supporting rod slidible 100

in said guide element, a passenger mount secured to the upper end of said supporting rod, a spring surrounding said supporting rod and bearing with its upper end against 5 said passenger mount and with its lower end against the upper end of said guide element, and means for giving said supporting rod a combined oscillating and vertical reciprocating movement whereby it is moved within 10 said guide element and causes said guide element to oscillate.

13. An amusement apparatus, comprising a truck adapted for movement over a pre-determined course, a shaft on said truck, 15 means for rotating said shaft, an eccentric on said shaft, an eccentric strap surrounding said eccentric, a guided supporting rod extending upwardly from said eccentric strap, a passenger mount secured to the upper end of said supporting rod, and means 20 for relieving said eccentric of the weight of said mount and the passenger carried thereby.

14. An amusement apparatus, comprising

a plurality of correspondingly trending 25 tracks, a third rail co-extensive with each track, a traveling unit on each track, a motor on each traveling unit, a contact on each traveling unit movable into engagement with or out of engagement from its co-operating 30 third rail and being in electrical connection with its co-operating motor, a source of electrical energy, electrical connections between said source of electrical energy and said motors and third rails, means for placing all 35 of said motors into action or out of action, means to selectively break connection between any of said motors and said source of electrical energy, and means to automatically move said contacts out of engagement 40 with their co-operating third rails when the traveling units carrying the same come in contact with traveling units ahead.

In testimony whereof we affix our signatures.
